UNITED STATES PATENT OFFICE.

HOWARD B. SHERMAN, OF BATTLE CREEK, MICHIGAN.

PROCESS OF MAKING CONNECTORS.

1,352,034.

Specification of Letters Patent.

Patented Sept. 7, 1920.

Application filed May 21, 1919, Serial No. 298,778. Renewed June 28, 1920. Serial No. 392,519.

To all whom it may concern:

Be it known that I, HOWARD B. SHERMAN, a citizen of the United States, residing at Battle Creek, in the county of Calhoun and State of Michigan, have invented certain new and useful Improvements in Processes of Making Connectors; and I hereby declare that the following is a full, clear, and exact description thereof, reference being had to the accompanying drawings, which form part of this specification.

This invention is a novel process of making novel connectors employed for connecting electrical wires.

The usual connector is a short metal sleeve and the wires from an electrical fixture are entered into one end of such sleeve and secured by a screw; and the end of the electrical supply wire is similarly connected to the other end of the sleeve by a similar screw. There may be a multiple of wires in the fixture, all of which are usually of the same gage, and the ends of such wires are entered into the same end of the sleeve and must be confined therein by the same screw. It is necessary to use separate set screws for the fixture wires and supply wires, because if the fixture wires and supply wires were of different gage one set screw could not properly secure them, because the smaller wire or wires would not be pinched or seated by such screw, as the larger wire would prevent the smaller wire being properly pinched by the screw. The said sleeve is also usually provided with some internal means, between the two set screws, to prevent wires inserted in one end of the sleeve projecting beneath the screw at the opposite end, which if the wires were not equal in diameter would cause the same difficulties which would arise if only one set screw were used.

These sleeve connectors are usually small and the screws very short, and therefore liable to be lost by being unscrewed too far in preparing the connector for engagement with the wires; as in backing out the screws to get ready to put in the wires, the workmen frequently withdraw the screws too far and they drop out; and being very short and small, if they drop out they are apt to be lost, or, at least, cause considerable annoyance and loss of time in searching for them. To prevent these annoyances the connectors have sometimes been provided

with means for preventing loss of the screws.

The object of the present invention is to make a simple and inexpensive sleeve connector by a novel method or process, such connector being so formed that both the fixture wires and the supply wire can be readily connected therewith and prevented from overlapping or passing each other, so that the screws will properly pinch the wires intended to be secured thereby; and the screws be securely retained in place in the connector.

The invention has particular reference to the method of making such connector which I will now explain in connection with the accompanying drawings which illustrate a novel connector and the process of making same, and will enable others to readily understand, adapt and use the invention; and I refer to the claims following the description for concise statements of the novel essentials of the invention for which protection is desired.

In said drawings:

Figure 1 is a perspective view of a complete connector.

Fig. 2 is a longitudinal sectional view thereof showing the wires attached.

Fig. 3 is a plan view of a blank for making such connector after it has been initially cut and pressed.

Fig. 4 is an enlarged end view showing such blank partially folded.

Fig. 5 is a similar view showing a flanged screw positioned in the blank.

Fig. 6 is an end view showing the completion of the folding operations.

Figs. 7 and 8 are longitudinal sectional views showing slight modifications of the partition.

The main body 1 of the connector is preferably formed out of a strip or blank of sheet metal, such as brass, so that it will be an excellent conductor. The blank is bent into a tube or sleeve, preferably substantially rectangular in cross section.

The size and cross sectional conformation of the body however is not restricted to the particular form shown in the drawings.

The blank is preferably so bent that the top *a* and side portions *b*, *b* are solid but the two end portions *c*, *c* are bent to form the bottom portion, such bottom blank having a longitudinal slit formed, as indicated at 1^a, 110

between the meeting ends of the parts *c*, *c* of the blank strip.

In the top portion *a* of the blank 1 is pressed a preferably centrally disposed transverse rib 1^b, which is preferably formed by pressing the strip so as to form a rib 1^b therein, which rib when the blank is folded will lie within the inner face of the top of the body, and be centrally disposed thereof 10 when the blank is bent into tubular shape, the rib leaving a corresponding depression in the outer face of the top.

In the opposite end portions *c*, *c* of the blank may be similarly pressed short ribs 1^c 15 which when the blank is folded to form the body meet and together form an inwardly projecting transverse rib corresponding in length and contour to rib 1^b and meeting therewith. The ribs 1^b, 1^c when the blank is 20 properly bent to form the body together constitute an internal partition extending across the inner space of the body and substantially closing same, so that the wires (*w*, *w'*) inserted in either end of the body will be 25 stopped by such partition (see Fig. 2) and cannot be passed through the body. If desired the ribs 1^c might be omitted and the rib 1^b made deep enough to form the partition; or instead of these ribs 1^b, 1^c the top *a* might 30 be centrally slotted and the ends of the slit bent inward to form a tongue or tongues 1^a, 1^a as in Fig. 7, such tongue or tongues serving as the partition; or the top may have short integral bent parts 1^o, 1^o (in place of ribs 1^b) and the bottom portions have short integral bent in parts 1^p, 1^p (in place of ribs 1^c) which parts 1^o, 1^p when the blank is folded form a partition, as shown in Fig. 8.

It will be seen that such a blank 1, for 40 forming the body, of the connector can be readily stamped out of sheet metal, with the portions 1^b, 1^c or 1^a pressed therein, and be afterward bent into box or tube form as shown in Figs. 1 and 6.

45 In the part *a* of the body forming the top of the connector are formed screw threaded openings 1^e at opposite sides of the partition; and each opening is engaged by a screw which (as shown) is preferably provided on 50 its inner end with an enlarged head or flange 2^b that preferably snugly fits between the side walls *b*, *b* of the complete body and will prevent any wires (*w*, *w'*) inserted therein passing or squeezing beside such screw when 55 it is clamped thereon, and insures that all the wires inserted under such screw will be engaged and held thereby when the screw is run down. The screw head 2^b also prevents the screw from being backed out of the connector and lost.

The preferred method or process of making such connectors is as follows:

The blank 1 of the proper size, indicated in Fig. 3, is stamped or cut from sheet metal 65 and may be provided at the time it is cut

from the metal or thereafter, at the proper point, with the pressed partition forming portions 1^b, 1^c or 1^a. The blank is thereafter bent along the dotted lines *a*, *b'*, *c'* (Fig. 3) by means of a suitable forming machine, or 70 by a suitable press, not shown, until the side portions *b*, *b* are at an angle of about 90° to the top portion *a*, while preferably the bottom portions *c* are bent at an angle of about 45° to the parts *b*, *b*; but sufficient space is 75 left between the extremities of the parts *c* for the insertion of the headed screws 2; which may then be engaged with the threaded openings 1^e, as indicated in Fig. 5; and thereafter by suitable means the folding of 80 the blank into the shell or tubular form is completed, as indicated in Fig. 6.

While this is the preferred method of making the connector so as to inclose and retain the headed screws, I do not consider the invention restricted to the particular sequence of steps recited. For example, it would be possible after stamping out the blank to insert the screws 2 and then fold in the side portions *b* and bottom portions *c*. Or the 85 side portions *b* might be folded to approximate position; then the screws 2 inserted; and then the bottom parts *c* folded. Or the parts *c* might be first folded relative to the parts *b* then the screws 2 inserted, then the 90 sides *b* folded to complete the tube.

The essential steps of the novel method of making the connector are: cutting the proper blank; providing the threaded openings therein; engaging the screws with the 100 openings and finally folding or completing the folding of the blank so as to inclose the headed portions of the screws and thus retain the screws permanently in position in the connector.

105 What I claim is:

1. In the process of making a tubular connector provided with screws; forming a blank provided with suitable threaded openings; engaging screws with the said threaded openings; and then completing the folding of the blank into tubular form to permanently retain the screws in the connector.

2. The process of making a connector of the character specified, consisting in forming a suitable blank to make a tube of the desired size, inserting screws having flanged or headed inner ends in the blank, and completing the folding of the blank to form a tube.

3. The method of making a connector of the character specified, consisting in forming a suitable blank to make a tube of the desired size, providing it with threaded openings; partly folding said blank into shape, inserting flanged or headed screws in the blank; and completing the folding of the blank to form a tube inclosing the heads of the screws.

4. The method of forming a connector,

consisting in cutting a blank of the desired width and length to form a tubular sleeve when folded, and pressing a part or parts of such blank relative to the body thereof in 5 such manner that when the blank is folded such part or parts will produce an internal partition within the connector.

5. The method of forming a connector, consisting in cutting a blank of the desired 10 width and length to form a tubular sleeve when folded, and pressing integral part or parts of the blank relative to the body thereof in such manner that when the blank is folded into a tube such part or parts will 15 produce an internal partition within the connector, and providing said blank with suitable threaded openings which when the blank is folded will lie at opposite sides of the partition formed by said portions.

20 6. The method of forming a tubular electrical connector consisting in cutting a metal blank of the proper width and length; and providing such blank with threaded holes for the reception of screws; partially folding the sides and ends of said blank to form the sides and bottom of the tube when the folding is completed; inserting in the threaded openings headed or flanged screws; then completing the folding of the sides and 25 ends of the blanks so as to inclose the heads or flanges of the screws within the tube.

30 7. The method of forming a connector, consisting in cutting a blank of the desired

width and length to form a tubular sleeve when folded, and pressing in said blank an 35 integral portion or portions which when the blank is folded will produce an internal partition within the connector; forming threaded openings in the blank which when the blank is folded will lie at opposite sides of 40 the partition; inserting in the threaded openings headed or flanged screws, then folding the blank so as to inclose the heads or flanged ends of the screws within the connector, substantially as described.

45 8. The method of forming a connector, consisting in cutting a blank of the desired width and length to form a tubular sleeve when folded, and pressing in said blank an 50 integral portion or portions which when the blank is folded will produce an internal partition within the connector; forming threaded openings in the blank which when the blank is folded will lie at opposite sides of 55 the partition; partially folding the sides and ends of said blank to form the sides and bottom of the connector when the folding is completed; inserting in the threaded openings headed or flanged screws; then completing the folding of the sides and ends of 60 the blank so as to inclose the heads or flanged ends of the screws within the connector, substantially as described.

In testimony that I claim the foregoing as my own, I affix my signature.

HOWARD B. SHERMAN.
